PACKAGE FOR DISPENSING POWDER

Archibald A. Moran, Mendham, N. J.

Application June 18, 1941, Serial No. 398,525

3 Claims. (Cl. 43—146)

This invention relates to a package for manually dispensing powder, such as a garden insecticide.

It has heretofore been proposed to provide bellows containers for dispensing powder. However, most of these containers have been expensive to manufacture and have had the disadvantage of not discharging the powder uniformly and evenly. They have discharged an excessive amount of powder when new, and much powder has been wasted. I have devised an improved bellows container, which is inexpensive to manufacture and which discharges an even spray of powder on each compression of the bellows.

The container or package which I have devised consists of a paper envelope including bellows folds connected between front and back panels along either side of the envelope. Perforated cardboards are placed against the inside faces of the front and back panels of the envelope. The container tapers from an expanded end to a narrow end where a notch is cut to permit discharge of the powder. At the narrow end of the container, the cardboards are arranged so that they prevent powder from passing directly to the notch between their ends. The powder is thus compelled to pass through the perforations in the cardboards and thence between the cardboards and the envelope in order to reach the notch. Each time the expanded end of the package is compressed a uniform spray of powder is discharged from the notch.

Other objects, features, and advantages of the present invention will become apparent or will be pointed out in connection with the following detailed description of an illustrative package in accordance with the invention, reference being made to the accompanying drawings wherein:

Fig. 1 is a plan view of the envelope before it is folded;

Figs. 2 and 3 are plan views of the cardboards;

Fig. 4 is a side elevation of the envelope after it has been folded into tubular form;

Fig. 5 is a vertical section showing the cardboards inserted in the tubular envelope;

Fig. 6 is a view similar to Fig. 5 but showing the large end of the package closed;

Fig. 7 is a view looking down toward the top of Fig. 6;

Fig. 8 is an enlarged section (approximately full size) taken through the package on line 8—8 of Fig. 9 after it has been filled with powder and after the small end of the package has been closed;

Fig. 9 is a horizontal section taken through Fig. 8, looking down;

Fig. 10 is a perspective, sectional view showing how the bellows and gusset are formed in each side of the envelope;

Fig. 11 is a front view of the package with the closure extended as in Fig. 6;

Fig. 12 is a view similar to Fig. 11, but with the closure in its final position as in Fig. 8, and with the notch cut in the package;

Fig. 13 shows a modified form of cardboard construction; and

Fig. 14 is a side elevation of the cardboard of Fig. 13 folded and ready for insertion in the envelope.

In Fig. 1 there is shown an envelope blank 15 which may be made out of any suitable heavy paper. The paper is preferably water repellent. The blank 15 is creased along the horizontal and vertical dot and dash lines and along the diagonal dot and dash lines, so that it can be readily folded to form the envelope. Dotted lines 16 are printed on the blank to show where the notch is to be cut. The blank includes a central portion 17 which forms the front panel of the envelope, portions 20 and 21 which form the bellows, and portions 18 which together form the rear panel of the envelope. The portions above the line e—f, including a flap 19, are folded to form a closure at the small end of the package. The portions below the line g—h form the other end of the package.

In making the package, the blank is first formed into a tube by bending it around a suitable mandrel so that the edges of the panels 18 and 19 abut or lie close together. A strip of paper 22, the same length as the blank 15, is pasted to the inside of the panels 18. This strip 22, as best shown in Fig. 9, overlaps the panels 18 sufficiently to form a tight closure. The panels 20 and 21 are then folded inwardly between the front and rear panels 17 and 18 with the fold between panels 20 and 21 lying at a—b—c—d as shown in Fig. 10. A gusset is formed by the two triangular portions between the points b and c. It will be understood that instead of using a separate strip of paper 22, one of the panels 18 may be made wider than the other so as to form a lap joint.

The cardboards used in the package are shown in Figs. 2 and 3 at 23 and 24 respectively.

Each of these cardboards is just a trifle smaller than panel 17 and has a number of perforations or pin holes 26 formed in it. Cardboard 23 has a notch 25 cut in one end to coincide with the dotted lines 16. If desired the notch 25 may be made larger than the area 16. Cardboard 24 is

creased along the line 27 and is slit as shown at 28 to form a flap 29 and hinged portions 30. Each of the portions 30 is approximately the same width as the distance between the inner corners of the bellows folds at the small end of the package. It will be understood that although cardboard has been mentioned as the material of which the members 23 and 24 are made, other stiff material may be used. The number and size of the pin holes may be varied, and, if desired, such pin holes may be omitted from one of the cardboards.

After the envelope has been formed into tubular shape, the cardboards are inserted in the envelope as shown in Fig. 5, the flap 29 being bent down. The portions of the blank between the lines *g*—*h* and *i*—*j* are then pressed upwardly to form the end portions 36 and 37 of the package. The portions of the blank below the line *i*—*j* are then doubled over and stapled as shown at 38 in Figs. 6 and 11. The portions 36 and 37 are then pressed inwardly to form a V as shown in Fig. 8. In this way, the two triangular portions of the gusset which lie between *b* and *c* in Fig. 10 are doubled against each other.

In order to complete the package it is only necessary to fill it with powder, fold the flap 19 and the portions of the envelope above the line *e*—*f* as shown in Fig. 8, and staple the doubled over portions of the package at opposite corners, so that the staples 39 pass through the hinged portions 30. The powder is thus sealed within the package.

In order to discharge the powder from the package it is only necessary to cut the notch in the envelope as shown in Fig. 12 and then grip the wide end of the package between the thumb and the fingers. Each time that the bellows are compressed powder is ejected through the perforations 26 in the cardboards and thence between the cardboards and the front and rear panels of the envelope to the notch where the powder is discharged from the package. By constructing the flap 29 as previously described the powder is prevented from passing directly to the notch between the ends of the cardboards. The flap 29 also helps to expand the bellows. By constructing the envelope and cardboards as previously described, the front and rear panels of the envelope bulge outwardly as shown in Fig. 8 so as to leave room for the powder to reach the discharge notch. Inasmuch as the rear panel of the envelope is of double thickness, and therefore stiffer than the front panel, it is preferable to insert the cardboard, including the flap 29, adjacent the rear panel. When the bellows are

compressed, the front panel bulges up to the notch, while the rear panel bulges sufficiently to permit powder to pass between it and the end 40 of the cardboard where flap 29 is hinged. It will be seen that in the construction described, only the cardboard 24 is hinged to the portions 30. If desired, cardboard 23 may be made the same as 24, and the flaps 29 on both members may be folded in to give additional spring action.

10 In Figs. 13 and 14 there is shown a modified form of the cardboards 23 and 24 in which both of them are scored on the dot and dash lines 27, and in which the two cardboards are made from a single sheet of material, including like portions 43 which are scored along the lines 44 and 45 and which are cut away as indicated at 46. Fig. 14 shows the manner in which these cardboards are folded for insertion in the envelope.

My package thus comprises an inner container and an outer envelope, the powder being retained in the inner container and being discharged upon the compression of the bellows through perforations in the inner container and thence between the inner container and the outer envelope to the discharge notch.

20 25 The terms and expressions which have been employed are used as terms of description and not of limitation, and there is no intention, in the use of such terms and expressions, of excluding any equivalents of the features shown and described, or portions thereof, but it is recognized that various modifications are possible within the scope of the invention claimed.

What I claim is:

30 35 1. A package of the character described comprising a tapering envelope having front and rear panels connected at either side by bellows folds, a pair of perforated cardboards lying within the envelope and adjacent the front and rear panels, 40 a discharge opening in the narrow end of the envelope, means to prevent powder from passing directly to the discharge opening between the ends of the cardboards, and means to close the ends of the envelope.

45 40 2. A package as claimed in claim 1, wherein the cardboards are just a trifle smaller than the front and rear panels of the envelope, and wherein the means to prevent powder from passing directly to the discharge opening comprises a flap on one of said cardboards bent over against the other cardboard at the small end of the envelope.

50 55 3. A package as claimed in claim 1, wherein said cardboards are joined by hinged sections.

ARCHIBALD A. MORAN.
